UNITED STATES PATENT OFFICE

124,877

DESIGN FOR AN ASH TRAY

John F. Schylander, Chicago, Ill.

Application May 6, 1940, Serial No. 92,173

Term of patent 7 years

To all whom it may concern:

Be it known that I, John F. Schylander, a citizen of the United States, residing at Chicago, in the county of Cook and State of Illinois, have invented a new, original, and ornamental Design for an Ash Tray, of which the following is a specification, reference being had to the accompanying drawing, forming a part thereof.

Referring to the drawing:

Fig. 1 is a perspective view of the ash tray showing my new design; and

Fig. 2 is a side elevational view thereof.

I claim:

The ornamental design for an ash tray, as shown.

JOHN F. SCHYLANDER.
